Primary Examiner — Cynthia Ramirez*Assistant Examiner* — Laura H Yu(74) *Attorney, Agent, or Firm* — McGarry Bair PC(57) **CLAIM**

The ornamental design for a bulk dispensing drawer, as shown and described.

DESCRIPTION

FIG. 1 is a top perspective view of a bulk dispensing drawer showing our new design;

FIG. 2 is a front view of the bulk dispensing drawer of FIG. 1;

FIG. 3 is a top view of the bulk dispensing drawer of FIG. 1;

FIG. 4 is a left side view of the bulk dispensing drawer of FIG. 1; and,

FIG. 5 is a right side view of the bulk dispensing drawer of FIG. 1.

Portions of the bulk dispensing drawer shown in broken lines form no part of the claimed design. The broken lines illustrating a washing machine are to show environment and form no part of the claimed design.
